SHIPBOARD ANTENNA SYSTEM

Jean Rebotier, Paris, France, assignor to Compagnie Generale de Telegraphic Sans Fil, a corporation of France

Application May 7, 1934, Serial No. 724,316
In France May 18, 1933

4 Claims. (Cl. 250—33)

The present invention has for its object the compensation of the effect on the control of antennas for wireless telegraphy installed on board of ships, produced by the rolling of the ships.

5 It is actually known that the rolling causes upon ships a variation of the antenna capacity and that consequently a periodic detuning is produced of the control of the transmitting and receiving apparatus coupled to this antenna. This 10 results in periodic variations of the intensity of the transmitting or receiving signals.

According to the invention this detuning is avoided by means of a compensating organ whose functioning is controlled by the same action, the influence of which is intended to be corrected, that is to say, by the inclination of the ship. Such action will be obtained for instance, by means of a pendulum or gyroscope.

20 The compensating organ proper will be very easily obtained by means of a variable condenser or a variable self inductance connected in series or in parallel to the antenna, or by means of circuits coupled to the latter.

The invention will be more clearly understood 25 by referring to the accompanying drawing, in which

Figure 1 illustrates a section through a ship which is off its normal vertical position;

30 Figure 2 is a section of a variable condenser wherein compensation is controlled by means of a pendulum;

Figure 3 is a section of a variable condenser wherein the pendulum forms the movable plate element of the condenser.

35 These figures shown simply as a matter of indication without intention of thereby limiting the invention, will facilitate a proper understanding of the principle of the invention.

Figure 1 shows at N a ship, whose antenna A, 40 assumed to be vertical if rolling does not occur, moves, as a result thereof, into an instantaneous inclination α . The apparent antenna capacity is shown at C in dotted lines. It is obvious that this capacity is a minimum if the antenna is in a 45 vertical position and that it increases with the inclination of the ship in accordance with a law depending upon the shape of the antenna.

Figure 2 shows the manner in which the compensation can be obtained by means of a variable 50 condenser controlled by a pendulum. In this figure 1 and 2 represent the two armatures of the condenser and 3 the pendulum. The armature 1 is fixedly secured to the ship thereby following the inclination α ; the armature 2, on the contrary, is maintained in the vertical position

by the pendulum. It will thus be readily seen that in this manner a capacity is obtained which is a maximum when the inclination is zero, and which decreases with increasing inclination.

Figure 3 shows a preferred embodiment of the invention whereby the pendulum proper forms one of the armatures 2 of the condenser. The other armature 1 will be formed for instance by two metallic plates fastened to the walls of a container, containing an insulating liquid, assuring the damping of the oscillations of the pendulum.

5 It is evident that the profile of the armatures 1 and 2 can be so shaped that a law of determined variation is obtained by which the variations of the antenna capacity C can be exactly compensated. In order to arrive at the simplest case it could be supposed that the condenser is mounted in parallel with the antenna capacity. In the similar case it suffices that, in order to maintain the tuning of the control means, that the sum of 10 the two capacities remains constant.

As is obvious to anyone versed in the art, other laws of variation or other relations between these capacities will be employed, if other circuits are utilized. For instance, the variable condenser of Figures 2 and 3 could be placed in series to the antenna instead of being connected in parallel thereto and these elements could be placed in circuits indirectly coupled to the antenna. As 15 above indicated, it should also be understood that the variable condenser could be replaced by a variable self inductance or other elements permitting the same result.

Finally it should be understood that the pendulum can be replaced by a gyroscope or any other 20 suitable stabilizing element.

I claim:

1. A shipboard antenna circuit comprising an aerial and a variable tuning element, and means 25 for automatically adjusting the said tuning element so that the proper frequency of the antenna circuit remains constant, said means being controlled by the rolling of the ship.

2. A shipboard antenna circuit comprising an aerial and a variable condenser connected therewith, and means controlled by the rolling of the ship 30 for automatically adjusting the said condenser so that the proper frequency of the antenna circuit remains constant.

3. A shipboard antenna circuit comprising an 35 aerial and a variable condenser connected therewith, an armature of this condenser being fixedly mounted relatively to the ship and a second armature being pivotally mounted so as to remain by the weight action in a constant position with re- 40

spect to the vertical line when the ship rolls, the said armatures being so shaped that the antenna circuit capacity remains constant during the rolling.

5 4. A shipboard antenna circuit comprising an aerial and a variable condenser connected therewith, an armature of this condenser being fixedly

and a second armature being pivotally mounted with respect to the ship, a pendulum attached to the said second armature, and means comprising a predetermined armature shape for maintaining the antenna circuit capacitance constant irrespective of the ship inclination. 5

JEAN REBOTIER.
